UNITED STATES PATENT OFFICE

JAMES L. CHANCE, OF RANGER, TEXAS

RIM TOOL

Refiled for application Serial No. 471,541, filed July 29, 1930. This application filed May 10, 1932.
Serial No. 610,493.

This invention relates to a rim tool and more particularly to a device of this character for use on vehicle tire rims of the type having thereon a collapsible latch, this application being filed in the place and stead of my former allowed application filed July 29, 1930, Serial No. 471,541.

Opening and closing rims equipped with a collapsible latch with an ordinary wrench or tool is a very difficult operation and when the rim passes dead center in either opening or closing its springs or snaps open or close suddenly with such force as to jerk the wrench or tool out of the hands of the operator or subjects the operator to considerable shock and perhaps injury.

The primary object of this invention is to provide, in a manner as hereinafter set forth, a rim tool embodying a novel construction and arrangement of parts including a rim engaging portion and an operating handle or lever which is operatively connected thereto in such a manner as to permit free rotation of the rim engaging portion independently of the handle or lever after the rim snaps past dead center in either opening or closing.

Another important object of the invention is to provide a rim tool of the aforementioned character having a wrench head thereon whereby same may be utilized as a lug wrench.

Another important object of the invention is to provide a rim tool of the character described wherein the operating handle or lever may be utilized as a tire iron or the like should it be so desired.

Other objects of the invention are to provide a rim tool which will be simple in construction, strong, durable, efficient in its use and which may be manufactured at low cost.

All of the foregoing and still further objects and advantages of the invention may become apparent from a study of the following specification, taken in connection with the accompanying drawing, wherein like characters of reference designate corresponding parts throughout the several views, and wherein:

Figure 1 is a view in side elevation of a rim

tool constructed in accordance with this invention, same being shown with the handle or lever disengaged from the abutment on the rim engaging rod,

Figure 2 is a view showing the tool in side elevation with the handle or lever engaged with the abutment and in position for actuating the rim,

Figure 3 is a top plan view of the tool,

Figure 4 is a detail view in top plan showing the end portion of the handle or lever which is rotatably connected to the rim engaging rod or bar.

Referring to the drawing in detail, it will be seen that the reference numeral 1 designates a rod which is preferably of circular cross section and is provided with a substantially wedge shaped rim engaging end 2. A socketed wrench head 3 is rigidly mounted on the opposite end of the rod 1. A substantially U-shaped abutment 4 is rigidly secured, as by soldering or welding to an intermediate portion of the rod 1, the opposite ends of the abutments being secured to the rod in spaced relation to the opposite ends of said rod.

Also mounted rigidly on the rod 1 in longitudinally spaced relation to each other and between the opposite ends of the abutments 4 are the collars 5. An operating handle or lever 6 is provided at one end with an eye 7 which rotatably encircles the rod 1 between the collars 5 and in this manner the rod 1 is rotatably mounted on the handle or lever 6. The free end of the handle or lever 6 is tapered or wedge shaped as at 8 to adapt said handle or lever for use as a tire iron or the like.

When used for opening or closing the rim, the wedge shaped end portion 2 of the rod 1 is engaged therewith and the handle or lever 6 is swung into engagement with the abutment 4 and a continuance of the swinging movement will impart rotation to the rod 1 in an obvious manner for opening or closing the rim. When the rim snaps past dead center the rod 1 will rotate ahead of the handle or lever 6 and thus all shocks or jerks on said handle from this source will be eliminated.

By forming the abutment 4 of substantially

U-shaped configuration and welding the opposite ends to the rod 1 great strength and durability is provided and the collars 5 maintain the rod 1 in such a position with respect to the handle or lever 6 that the intermediate portion of the abutment 4 which is farthest away from the rod 1 will be engaged by said handle or lever 6.

When the device is to be used as a lug wrench, the head 4 is engaged over the nut to be actuated and the rod 1 rotated by engaging the handle or lever 6 with the abutment 4 in the same manner as when operating the rim. As before stated, the tapered or wedge shaped end portion 8 of the handle or lever 6 may be used as a tire iron or other tool.

It is believed that the many advantages of a rim tool constructed in accordance with this invention will be readily understood, and although the preferred embodiment of the invention is as illustrated and described, it is to be understood that changes in the details of construction may be had which will fall within the scope of the invention as claimed.

Having thus described my invention, what I claim as new is:

1. A rim tool of the character described comprising a rim actuating rod, a substantially U-shaped abutment rigidly mounted on the rod, and an operating lever rotatably connected to the rod and engageable with an intermediate portion of the abutment for limiting the rotary movement of the lever on the rod.

2. A rim tool of the character described comprising a rim actuating rod, a substantially U-shaped abutment rigidly mounted on an intermediate portion of the rod, the opposite ends of the abutment being secured to the rod, and an operating lever rotatably connected to the rod intermediate the ends of the abutment and engageable with an intermediate portion of the abutment in a manner to limit the rotary movement of the lever independently of the rod.

3. A rim tool of the character described comprising a rim actuating rod, a substantially U-shaped abutment rigidly mounted on an intermediate portion of the rod, the opposite ends of the abutment being secured to the rod, a pair of collars mounted in longitudinally spaced relation to each other on the rod between the opposite ends of the abutment, and an operating lever rotatably connected to the rod between the collars and engageable with an intermediate portion of the abutment for limiting the rotary movement of the lever independently of the rod.

60 In testimony whereof I affix my signature.
JAMES L. CHANCE.
